UNITED STATES PATENT OFFICE.

JOHN H. SHAW, OF NEW HAVEN, CONNECTICUT.

WALKING TOY.

1,332,073.

Specification of Letters Patent. Patented Feb. 24, 1920.

Application filed June 4, 1919. Serial No. 301,704.

To all whom it may concern:

Be it known that I, JOHN H. SHAW, a citizen of the United States, residing in the city and county of New Haven, State of Connecticut, have invented certain new and useful Improvements in Walking Toys, of which the following is a full, clear, and exact description.

This invention relates to walking toys, and more particularly to dolls or the like constructed to simulate more or less accurately the walk of a human being, although it will be apparent that the mechanism herein disclosed may equally as well be applied to toy animals provided with either two or four legs.

The primary object of my invention is to improve the operation of walking toys and particularly the type of toys which are designed to be rocked from side to side during the walking operation to permit each foot to clear the floor as it is being advanced.

A more specific object of my invention is to construct the feet of the type of toy, just referred to, so that each foot, while being advanced, will clear the floor when a very small amount of lateral rocking movement is imparted to the toy.

Another object of my invention is to provide means whereby the operation of the type of walking toy to which this invention relates may be materially improved without increasing the cost of manufacturing the same.

To these and other ends the invention consists in the novel features and combinations of parts to be hereinafter described and claimed.

In the accompanying drawing:

Figure 1 is a front view of a doll embodying my invention, the doll being shown tilted slightly to the left to permit one foot to clear the floor as it is swung to its forward position.

Fig. 2 is a view similar to Fig. 1 showing the doll tilted slightly to the right in order that the other foot may clear the floor as it is swung to its forward position.

Fig. 3 is a side view of Fig. 1, a part of the doll being broken away to show the pivotal connection between the leg and body.

Fig. 4 is an enlarged sectional view taken

on the line 4—4 of Fig. 3 looking in the direction of the arrow; and

55

Fig. 5 is an enlarged front view of a shoe having the sole thereof constructed in accordance with my invention.

In the embodiment of my invention illustrated in the drawing, I have shown a toy doll having a one-piece head and body or trunk designated by the numeral 10, and having legs 11 and 12 pivotally secured to the trunk 10 by means of pivot pins 13, which pins extend transversely through the upper portion of each of the legs and through the lower portion of the downwardly projecting posts 14. The upper ends of which posts are rigidly secured in the body portion 10. The body portion 10 has spaced concaved sockets 15 formed in the lower end thereof to provide clearance spaces for the upper rounded ends of the pivoted legs 11 and 12. The legs are in this manner pivotally secured to the body portion of the toy, so that they may be freely swung back and forth relatively to the body portion or trunk 10, and these legs are normally swung to their forward position by a bent spring 16 seated in a slot 17 formed in the post 14, with one end of this spring abutting against the post and the other end abutting against a portion of each leg above the pivot pin 13. The construction and operation of the walking toy, so far described, is more fully disclosed and described in my copending application, Serial No. 276,133, filed February 10, 1919, in which application the means for advancing the legs to their forward position is claimed. Since the construction, so far described, forms no part of the present invention, it is unnecessary to give a more detailed description of the same.

In order that the type of walking toy to which my invention relates may swing one of its legs to the forward position while the weight of the toy is supported by the other leg, it is necessary to provide clearance between the floor or the like, and the bottom of the foot being advanced; otherwise the free movement of the foot to its forward position will be interfered with by the same dragging over the floor. The simplest way to obtain this necessary clearance between the floor and the advancing foot is to tilt

the toy transversely slightly in one direction until one foot is advanced, and then tilt the toy in the opposite direction while the other foot is being advanced. In order 5 to increase the clearance between the floor or the like and the bottom of the foot which is being advanced, I have cut away the soles of the feet or shoes with which my walking toy is provided, as indicated by the numeral 10 17, the soles being cut away in such a manner that only the marginal portion of the sole of each foot adjacent the outside of the foot engages the surface upon which the toy walks. In this manner, the extent to 15 which the walking toy need be rocked laterally in first one direction and then the other is materially reduced, so that it is necessary to impart only a very slight lateral swaying movement to my toy, in order that first one foot and then the other may 20 be advanced by the spring 16, as the same walks upon a supporting surface. The effect in cutting away the bottoms of the feet or the soles of the shoes, as indicated 25 by the numeral 17, is to make the distance as great as possible between the portion of one foot that engages the floor and the corresponding portion of the other foot which engages the floor without increasing 30 the distance between the legs 11 and 12. The floor or surface upon which the toy walks is indicated by the numeral 18, and the engagement of the outer marginal edge of the sole of the feet or shoes with this 35 surface 18 is clearly shown in the drawing. This construction is desirable, since when the toy is rocked laterally, it rocks upon the outside marginal edge of the sole of first one foot and then upon the outside 40 marginal edge of the sole of the other foot, and the greater the distance between these portions of the feet or shoes which engage the supporting surface, the smaller the angle through which the toy must be rocked 45 in a lateral direction to cause the free foot to clear the supporting surface while it is being advanced. In this manner I obtain a walking toy which requires a very small lateral rocking movement to be imparted to 50 the same in order to permit first one foot and then the other to clear the supporting surface while the same is being moved to its forward position, and this object is obtained without spacing the feet apart to 55 such an extent that the toy would be given an unnatural appearance. This desirable operation is due to the fact that by constructing the feet of the toy so that the marginal portion of each sole adjacent the 60 other foot is prevented from engaging the surface 18, each foot clears the supporting surface as soon as the marginal portion of the sole adjacent the outside of the foot is lifted out of engagement with the same. 65 It is apparent that a walking toy of the

type to which this application relates may have the feet of the same cut away as indicated in this application, or that the walking toy may be provided with shoes, the soles of which are cut away, as herein set forth, and it is also apparent that the soles of the feet or shoes may be constructed in various different ways to obtain the operation herein described, without departing from the scope of my invention, as defined 75 in the annexed claims.

What I claim is:

1. A walking toy having legs pivotally secured to the body thereof, resilient means for swinging said legs about their pivot to 80 the advance position, and feet upon said legs, said feet having the soles thereof cut away so that only the marginal portion of the sole adjacent the outside of the foot engages the surface upon which the toy walks, 85 to thereby increase the clearance between each foot and the supporting surface while the foot is being advanced.

2. A walking toy having legs pivotally secured to the body thereof, said legs arranged to be swung about their pivot from the rearward to the advance position, and feet upon said legs, said feet having the soles thereof cut away so that only the marginal portion of the sole adjacent the outside of the foot engages the surface upon which the toy walks, to thereby increase the clearance between each foot and the supporting surface while the foot is being advanced. 90 95

3. A walking toy having legs pivotally secured to the body thereof, means for swinging said legs about their pivot to the advance position when the toy is tilted slightly sidewise, and feet upon said legs, said feet having the soles thereof cut away so that only the marginal portion of the sole adjacent the outside of the foot engages the surface upon which the toy walks, to thereby increase the clearance between each foot 100 and the supporting surface while the foot is being advanced, whereby when the walking toy is tilted slightly sidewise upon one foot the other foot will clear the supporting surface as it is advanced by said swinging 110 means. 105

4. A walking toy having legs pivotally secured to the body thereof, means for swinging said legs about their pivot to the advance position, and feet upon said legs, said feet having the marginal portion of their soles adjacent the outside of each foot constructed to extend downward beyond the remaining portion of said soles whereby only this marginal portion of each sole engages the surface upon which the toy walks, to thereby increase the clearance between each foot and the supporting surface while the foot is being advanced. 115 120 125

5. A walking toy having legs pivotally 130

secured to the body thereof, said legs arranged to be swung about their pivot from the rearward to the advance position, and feet upon said legs, said feet having that 5 portion of their soles which lies nearest the other foot cut away to at all times clear the surface upon which the toy walks.

6. A walking toy having legs pivotally secured to the body thereof, means for 10 swinging said legs about their pivot to the

advance position, and feet upon said legs, said feet having that portion of their soles which lies nearest the other foot cut away to at all times clear the surface upon which the toy walks, to thereby increase the clearance between each foot and the supporting surface while the foot is being advanced. 15

In witness whereof I have hereunto set my hand on the 2d day of June, 1919.

JOHN H. SHAW.
